DESIGN FOR A LENS GRINDING HOLDER

Roswell V. Williams, Milwaukee, Wis., assignor to
Ralph W. Kendrick, Aurora, Ill.

Application November 26, 1947, Serial No. 142,830

Term of patent 14 years

(Cl. D37—1)

To all whom it may concern:

Be it known that I, Roswell V. Williams, a citizen of the United States and a resident of the city of Milwaukee, in the county of Milwaukee and State of Wisconsin, have invented a new, original, and ornamental Design for a Lens Grinding Holder, of which the following is a specification, reference being had to the accompanying drawing, forming part thereof.

Fig. 1 is a perspective view of a lens grinding holder, showing my new design;

Fig. 2 is a top plan view of the lens grinding holder; and

Fig. 3 is a vertical sectional view taken along the line 3—3 of Fig. 2.

I claim:

The ornamental design for a lens grinding holder, as shown.

ROSWELL V. WILLIAMS.
